HAND MAGNIFIER

Paul A. Hoogesteger, Brighton, and Richard L. Pitchford, Brockport, N.Y., assignors to Bausch & Lomb Incorporated, Rochester, N.Y., a corporation of New York

Filed Dec. 4, 1962, Ser. No. 72,715

Term of patent 14 years

(Cl. D57—7)

FIG. 1

FIG. 2

FIG. 3

FIG. 4

FIG. 1 is a top plan view of a hand magnifier in closed position showing our new design;

FIG. 2 is a side view of said magnifier;

FIG. 3 is a bottom plan view of said magnifier where-
in said magnifier is in an open position; and,

FIG. 4 is a fragmentary sectional view taken on line
4—4 of FIG. 1.

The side not shown has substantially the same appear-
ance as the side shown.

We claim:

The ornamental design for a hand magnifier, substan-
tially as shown and described.
